SUPPORT STAND FOR AN EDUCATIONAL KIT OR THE LIKE

Charles F. Pohlmann, Minneapolis, Minn., assignor to
General Electric Company, a corporation of New York

Filed Nov. 19, 1962, Ser. No. 72,538

Term of patent 3½ years

(Cl. D25—1)

FIG. 1.

FIG. 2.

FIGURE 1 is a perspective view of a support stand for an educational kit, looking toward the front thereof, showing my new design, the side not shown being substantially a mirror image of the side shown, and

FIGURE 2 is a perspective view of the support stand, looking toward the rear thereof.

The side not shown is substantially a mirror image of the side shown.

I claim:

The ornamental design for a support stand for an educational kit or the like, substantially as shown and described.
